UNITED STATES PATENT OFFICE.

WILLIAM B. WAIT, OF NEW YORK, N. Y.

PLATE-HOLDING DEVICE.

1,090,664.

Specification of Letters Patent. Patented Mar. 17, 1914.

Application filed June 5, 1913. Serial No. 771,912.

To all whom it may concern:

Be it known that I, WILLIAM B. WAIT, a citizen of the United States, residing at New York, in the county of New York and 5 State of New York, have invented new and useful Improvements in Plate-Holding Devices, of which the following is a specification.

This invention relates to a plate holding 10 device for attaching and adjusting an embossing or printing device on to the cylinder or bed of an embossing or printing press.

The plate consists of thin flexible metal, and it is the principal object of the invention 15 to strain the plate on to the cylindrical support and hold it securely in place while it is in action.

The holding devices consist of a jaw which coacts in combination with a shaft 20 for clamping the plate securely to the cylinder. One of the main objects of the invention resides in the peculiar method of actuating the jaw so that the plate can readily be adjusted to the proper position or alignment 25 on the cylinder, or when desired can be quickly removed. The support carries a plurality of shafts to which the plate is connected and by operating a shaft the plate can be snugly seated on the cylinder, and at 30 the same time the tail of the plate is securely clamped by means of the movable jaws in connection with its shaft.

Further details of the invention are more 35 fully described in the following specification and claims and illustrated in the accompanying drawings in which:

Figure 1 represents a side elevation of a 40 cylindrical support embodying this invention. Fig. 2 is a plan view of the same. Fig. 3 is a vertical detail section taken along the line $\alpha\alpha$ Fig. 2. Fig. 4 is a similar section showing the clamp in a different position.

In this drawing the letter a designates a 45 support or cylinder and b is a plate supported on the cylinder and preferably adapted for embossing characters on a sheet of paper. The cylinder has the usual recesses or gaps c located in the periphery of the cylinder. 50 These recesses serve to house the plate holding devices as will be hereinafter described. The cylinder carries a series of shafts d and e respectively extending the length of the recess and journaled in the side walls of the cylinder. The shafts have angular ends so 55 that a key or wrench can be employed to

turn the shaft. Each shaft has a ratchet f with a pawl g to prevent reverse movement of the shaft. The pawl can be moved out of engagement with the teeth of the ratchet by 60 means of a device h such as a set screw. The shaft d is provided with hooks i for engaging perforations located near one end of the plate. This portion of the plate constitutes the head, and the tail end is clamped between a jaw j and the said shaft e . 65

The devices for operating the jaw comprise a plunger k best seen in Figs. 3 and 4, slidably mounted in a slotted tubular post m fixed in a recess. The jaw is fulcrumed at 70 n to an upper extension of the post. To the upper portion of the plunger is pivoted one end of a link o the other end of the link being connected to the jaw. To the lower end of the plunger is pivoted another link p which is 75 connected to a lug q located at the lower portion of the said shaft e . The under side of the jaw is provided with a projecting device r of suitable construction to engage a notch or depression in the tail of the plate. 80

When it is desired to place a plate in position on the cylinder, the head thereof will hook on to the shaft d and the pawls moved from the teeth of the ratchet, the head of the plate is then positioned on to the shaft e 85 and the shaft is operated by means of a key to swing the jaw into the position shown in Fig. 3, to clamp the plate between the shaft and the jaw. The pawls are then moved into engagement with the teeth of the ratchet and the shaft d rotated to strain or seat the plate. When the plate is to be removed from the cylinder all that is necessary, is to move the pawls out of engagement with the ratchet and rotate the shaft e 90 to oscillate the jaw upward as indicated in Fig. 4. 95

It will be seen that when the shaft e is rotated to swing the jaw downward toward the shaft the pawl clicks over the teeth of the ratchet and the jaw is thereby locked by preventing retrograde movement of the shaft. 100

I claim:

1. In a plate holding device, the combination with a support having a plate mounted thereon, of a shaft carried by the support, a jaw to engage the shaft for clamping the plate against the shaft, and means actuated by the shaft for oscillating the jaw. 105
2. In a plate holding device, the combination with a cylindrical support having a 110

plate mounted thereon, of a shaft carried by the support, a jaw to engage the shaft for clamping the plate against the shaft, and means operated by the shaft for oscillating the jaw to release the plate.

3. In a plate holding device, the combination with a cylindrical support having a plate mounted thereon, of a shaft rotatively carried by the support, a jaw to engage the shaft for clamping the plate against the shaft, means operated by the shaft for oscillating the jaw, and means for locking the jaw.

4. In a plate holding device, the combination with a cylindrical plate support having a plate mounted thereon, of a shaft rotatively carried by the support, a jaw to engage the shaft for clamping the plate against the shaft, means operated by the shaft for oscillating the jaw, and means engaging the shaft for locking the jaw.

5. In a plate holding device, the combination with a cylindrical support having a plate mounted thereon, of a shaft rotatively carried by the support, a jaw to engage the shaft for clamping the plate against the shaft, a plunger connected to the jaw, and means operated by the shaft for actuating the plunger to move the jaw.

30 6. In a plate holding device, the combination with a cylindrical plate support, of a shaft rotatively carried by the support, a jaw to engage the shaft for clamping the plate against the shaft, a plunger linked to the jaw, and means connected to the shaft for oscillating the jaw.

nation with a cylindrical plate support, of a shaft rotatively carried by the support, a jaw coacting with the shaft for clamping the plate against the shaft, a plunger linked to the jaw, and means connected to the shaft 35 and the plunger for oscillating the jaw.

7. In a plate holding device, the combination with a cylindrical plate support, of a shaft rotatively carried by the support, a jaw coacting with the shaft for clamping 40 the plate, a plunger linked to the jaw, a link pivoted to the shaft, and connected to the plunger for oscillating the jaw.

8. In a plate holding device, the combination with a cylindrical plate support, of a pair of shafts rotatively mounted on the support, a jaw to engage one of the shafts 45 for clamping one end of the plate against the shaft, the other end of the plate being connected to the other shaft, and means for preventing retrograde movement of the shaft to lock the jaw.

In testimony whereof I have hereunto set my hand in the presence of two subscribing witnesses.

WILLIAM B. WAIT.
